UNITED STATES PATENT OFFICE.

SAMUEL CALHOUN, OF EDINBURG, OHIO.

SPRING BED-BOTTOM.

SPECIFICATION forming part of Letters Patent No. 237,726, dated February 15, 1881.

Application filed September 1, 1879.

To all whom it may concern:

Be it known that I, SAMUEL CALHOUN, of Edinburg, Portage county, Ohio, have invented a new and useful Improvement in Spring Bed-Bottoms, of which the following is a specification.

The invention relates to spring bed-bottoms having adjustable spring-heads.

The object of my invention is to provide a windlass having its cord connected with a hinged arm or arms for elevating and lowering the spring-head; also, to adjust by screws the relative positions of the cross-bars which support the spring-bottom, to connect the springs and slats by hooks, and to provide the head-slats with links and springs lengthwise from the lower ends of the slats and connected with a rock-shaft.

In the drawings, Figure 1 is a plan. Fig. 2 is a longitudinal vertical section. Fig. 3 represents the connection of a slat with its spring by a link.

The ends of cross-bars a^2 a^2 , which support slats e' , with their springs s , rest in boxes z . These boxes are attached to the inside of rails a a near the head and foot of the bed, and are open toward the foot and the opposite side of the bed to admit the cross-bars a^2 . The bottom slats, e' , rest on springs s , attached to cross-bars a^2 by clasps n , which are firmly pressed on the wire forming the spring by screws entering the cross-bar. Each of springs s is formed of two wire spirals at each side of slat e' , connected by the wire passing under the slat through hook x . The double hook x connects spring s with slat e' by entering a hole through the slat. At each end of one of the cross-bars a^2 a screw, o' , passing through the cross-bar and the end of box z , is provided, with a threaded nut, o . When slats e' have been placed in position with hooks x in the holes of the slats, by turning nut o on screw o' to force the cross-bars farther apart, the hooks x , connected with springs s on each cross-bar a^2 a^2 , are thereby drawn against opposite sides of the two series of holes in slats e' for the purpose of preventing the hooks x from becoming dislodged from the holes in the slats.

By turning nut o in the opposite direction

hooks x become loose in slats e' , so that the slats may be removed from the hooks and replaced with their bottom sides up when they have become slightly bent by long-continued use. Spring s projects above the bottom of slat e' , on each side of it, and thus acts as a lateral brace to the slat.

The elevator or spring-head, composed of a series of slats, c^2 , with their springs and frame, turns on its rock-shaft c' in side rails, a a . Its frame is formed of the rock-shaft, side bars, e e ; and upper cross-bar, b . The bars e e are bent or curved upward over cross-bar a^2 to permit the head-slats c^2 to be sufficiently lowered. Slats c^2 , near their upper ends, are connected with cross-bar b by springs s^2 , which are similar to springs s . Bar b , springs s^2 , and slats c^2 are connected in the same manner as bars a^2 , springs s , and slats e' , except that springs s^2 are attached to the under side of their slats by wire staples. The lower end of each head-slat c^2 is connected with rock-shaft c' by link x' and spring g . One end of the wire forming the spiral spring g extends back through the spiral and rock-shaft c' , where it forms a loop or hook, which is connected with the lower end of slat c^2 by link x' , both link and spring being in line with the slat.

The head-slats are elevated and lowered by means of a windlass consisting of a roller, f , turning in side rails, a a , by applying a crank at one end, and the ropes or cords s s' , attached to the lower end of the curved arm w . Arm w is formed of a rod bent as shown in Figs. 1 and 2, and having its upper ends hinged to cross-bar b . In raising and lowering the head-slats the direction of arm w is changed by its contact with the top of roller f , against which it slides, to prevent the lower end of the arm striking either the bed or the floor on which the bed stands. The ratchet-wheel a' on roller f near one end connects with pawl c , which turns on a pin in the inner side of rail a . When the head-slats c^2 are to be lowered pawl c is disconnected with ratchet-wheel a' by pressing with the hand on small lever v , having its fulcrum on rail a , and connected by link v' with pawl c .

I claim as my invention—

A spring bed-bottom provided with a head-elevator, in which the head-slats, at their upper ends, rest on springs, and are connected at their lower ends with the spiral springs g by 5 intermediate links, x' , hinge-jointed to the slats c^2 and springs g , in combination with a rock-shaft, c' , situated between links x' and springs

g , the slat c^2 , link x' , and spiral spring g being in line with each other, substantially as described.

SAMUEL CALHOUN.
